CASING FOR CREDIT CARD VERIFICATION SYSTEM

Richard C. Hutchinson, Redondo Beach, Calif., assignor
to American Computer and Communications Com-
pany, Palos Verdes Estates, Calif., a corporation of
California

Filed July 1, 1968, Ser. No. 12,583

Term of patent 14 years

Int. Cl. D18—03
U.S. Cl. 64—11

Fig. 1.

Fig. 2.

Fig. 3.

FIG. 1 is a perspective view of a casing for credit card verification system, showing my new design;

FIG. 2 is a rear elevation view; and

FIG. 3 is a right side elevation view.

The dominant features of the design reside in the portions shown in full lines.

I claim:

The ornamental design for a casing for credit card verification system, substantially as shown and described.
